[57] CLAIM

The ornamental design for a desk top organizer, as shown and described.

DESCRIPTION

FIG. 1 is a top, left front isometric view of a desk top organizer showing our new design;

FIG. 2 is a top plan view thereof in which the front of the desk top organizer is raised slightly with respect to the back of the desk top organizer such that a plane defined by the bottom surface of the desk top organizer is tilted at an angle of eight degrees to the horizontal about a horizontal axis parallel to the back of the desk top organizer;

FIG. 3 is a left side elevational view thereof;

FIG. 4 is a right side elevational view thereof;

FIG. 5 is a bottom plan view thereof;

FIG. 6 is a front elevational view thereof; and,

FIG. 7 is a rear elevational view thereof.

FIG. 1

FIG. 2

FIG. 3

FIG. 4

FIG. 5

FIG. 6

FIG. 7
